Attorney, Agent, or Firm—Knobbe, Martens, Olson & Bear

[**] Term: 14 Years

CLAIM

[21] Appl. No.: 15,684

The ornamental design for the combined putter and wedge golf club head, as shown and described.

[22] Filed: Nov. 24, 1993

DESCRIPTION

[52] U.S. Cl. D21/214

FIG. 1 is a front perspective view of a combined putter and wedge golf club head showing my design;
FIG. 2 is a rear perspective view thereof;
FIG. 3 is a front elevational view thereof;
FIG. 4 is a front end elevational view thereof;
FIG. 5 is a rear elevational view thereof;
FIG. 6 is a bottom view thereof; and,
FIG. 7 is a top view thereof.

[58] Field of Search D21/217-220;
273/164.1, 167-175

The broken line showing of a fragmented shaft is for illustrative purposes only and forms no part of the claimed design.
